SUPPORT APPARATUS

Tefius X. Dectrow, Philadelphia, and Harold C. Sundby, Roslyn, Pa., assignors to Minneapolis-Honeywell Regulator Company, Minneapolis, Minn., a corporation of Delaware

Filed Sept. 26, 1957, Ser. No. 686,418

1 Claim. (Cl. 248—223)

The present invention relates to a bracket which may be located in any one of four positions and still provide a means by which an object, such as a casing, may be mounted in an upright position on a stationary support member.

A general object of the present invention is to provide a bracket which may be mounted in any one of four positions on any type of a support member and still provide the same type of key hole slot-supporting bolt connection for an object that is to be mounted thereon.

Prior to the present invention it has been necessary to provide instrument casings with lugs having a plurality of irregularly spaced apart key shaped slots so that such lugs could be placed over and then locked to bolts that projected from a support member on which the casing was vertically mounted. Experience has shown that when inexperienced assembly men are employed to mount these casings, particularly the casing of a non-indicating instrument, that they sometimes incorrectly mount such instruments in an upside down position rather than in their correct upright position. Components are often placed in these casings which can perform their function satisfactorily in either of the two aforementioned positions. However when such casings are mounted in an upside down position the key shaped slots will then not be in a position to be placed over the bolts projecting from the support member so that they may be lowered into the narrowest portion of their associated key slot. Instead, these bolts will only be brought into supporting contact with the surface that forms the widest diametral portion of the slot.

As each of the bolts projecting from the stationary support under the aforementioned mounting conditions is only in engagement with the large portion of the key slot and the outside diameter of each bolt is considerably smaller than its associated large portion an undesirable amount of movement can therefore take place between the instrument and each of these mounting bolts. It is thus evident that this casing cannot therefore be securely mounted to a support member if it is inadvertently mounted in the aforementioned upside down position.

It is thus another object of the present invention to prevent this incorrect mounting of such a casing from occurring by providing a single bracket that has a back surface that can readily be fixedly connected to a vertical or horizontal pipe, or any other support member, and that also has a front surface that contains four equally spaced quadruple key shaped slots into which bolts that project from the back of the casing may be securely mounted.

It is thus another specific object of the present invention to provide a support bracket having four quadruple key slots in each of its four corners into four narrow groove portions of which four associated support bolts of a casing may be engaged to enable these supporting bolts to always be placed in their correct supporting position in each of these bracket slots regardless of whether

2

the position of the bracket is in one or another of two vertically or two horizontal positions.

A better understanding of the present invention may be had from the following detailed description when read in connection with the accompanying drawing in which:

Fig. 1 shows a rear elevation of a bracket disclosed in this application connected to a stationary vertically positioned support member.

Fig. 2 shows a sectional view of the bracket taken on the lines 2—2 of Fig. 1.

Fig. 3 shows a rear elevation of the bracket connected to a stationary horizontally positioned support member.

Fig. 4 shows the position that the slots in the bracket shown in Fig. 1 will be in when the bracket is turned either 180 degrees clockwise or counterclockwise from its Fig. 1 position.

Fig. 5 shows the position that the slots in the bracket shown in Fig. 1 will be in when the bracket is turned either two-hundred and seventy degrees clockwise or ninety degrees counterclockwise from its Fig. 1 position.

The bracket shown in Fig. 1 of the drawing may be constructed of a unitary flat steel plate material or made of any other material such as molded plastic material. As shown, this bracket plate 1 is of an H-shaped configuration and is provided with four corner portions 2, 3, 4, and 5. A cylindrical aperture such as the aperture 6, 7, 8 and 9 are shown in each of the corner portions. The centers of each of the cylindrical apertures 6, 7, 8 and 9 are shown located in such a manner that they are equally spaced from the center of the bracket 1, and are circumferentially spaced ninety degrees apart from one another.

Each of the four slots, 11, 12, 13 and 14 shown in the corner portion 2 of the bracket 1 is shown as having one of their ends opening into the aperture 6.

The slots 15, 16, 17 and 18 which are shown in the corner portion 3, the slots 19, 21, 22 and 23 in the corner portion 4 and the slots 24, 25, 26 and 27 in the corner portion 5 are all located in their respective corner portions in an identical manner to that already described for the slots 11—14 in the corner portion 2.

Figures 1 and 2 of the drawing shows the central portion of the aforementioned bracket 1 as having an elongated dished out portion 28, 29, 31 of a U-shaped configuration. This central portion is also shown as having an elongated slot formed by the wall portions 32, 33, 34 and 35 of the dished out portions 28, 29 and 31. The part 29 of the dished out portion is also shown as having two spaced apart apertures 36, 37 through which the brackets may be attached to a stationary support member.

The arrangement disclosed in Figures 1 and 2 of the drawing makes use of these apertures 36, 37 to attach the wall portion 33, 34 of the bracket 1 to a vertically positioned stationary pipe 38 by means of a commercially available threaded U-bolt 39 and a bolt locking means that consists of the two flat washers 41, 42, two spring washers 43, 44 and two locking nuts 45, 46.

While these apertures are shown in Figs. 1 and 2 as being used to attach the bracket 1 to a stationary pipe 38 it should be understood that other types of threaded members such as bolts can be placed through these apertures 36, 37 and into threaded engagement with tap holes in a support member that has a flat surface so that the surface 29 of bracket may be flush mounted on such a surface.

In order to lighten the weight of the bracket without affecting its supporting strength the lower central portion 31 of the bracket adjacent the corner portions 4 and 5 contains a slot 47 as can best be seen in Fig. 2 of the drawing. A slot 48 that is identical to the slot 47 is also cut in the lower central portion 28 of the bracket 1.

In Figs. 1 and 2 of the drawing there is shown pro-

jecting through the slots 26 and in closed tolerance therewith the shank of a tap bolt 49. The threaded end of this bolt is shown engaged with threads in the tap hole 51 that is in the back wall 52 which wall represents a casing or any other object that is to be supported by bracket 1 on the stationary support 38. Other tap bolts 53, 54 and 55 are shown in Fig. 1 being used to support the casing 52 on the slotted out portions of 13, 17 and 22 of the bracket 1 in the same manner as that described supra for the bolt 49.

It should be noted that the present bracket is not limited to casings having mounting members in the form of tap bolts as described supra but is also useful in mounting casings having many other forms of cylindrical mounting members projecting therefrom such as stud bolts, etc.

Fig. 3 shows the bracket 1 turned circumferentially ninety degrees in a clockwise direction from the position noted in Fig. 1 and the bracket mounted on a horizontally positioned stationary support pipe 56. This figure also shows that the cross shaped slots in the bracket 1 can accommodate the mounting of support bolts projecting from the back of the casing 52 on a stationary member 56 in the same way it accommodated these same bolts when the position of the bracket 1 was in the position shown in Fig. 1.

Fig. 4 shows the position that the corner portions 2-5 will be in to receive the bolts 49, 53, 54 and 55 when the bracket has been turned circumferentially another ninety degrees in a clockwise direction from the position shown Fig. 3.

Fig. 4 also shows a solid line cross sectional view of the position that the shank of bolts 49, 53, 54 and 55 will be in when the casing into which these bolts are threaded is initially placed against the bracket 1. This Fig. 4 showing also discloses a dotted line position in the slots 19, 24, 11 and 15 into which the shank of the bolts 49, 53, 54 and 55 are slidably mounted before these bolts are each tightened into a secure position such as the secure position shown for the bolt 49 in Fig. 2.

Fig. 5 shows another solid line cross sectional view of the position that the shank of the bolt 49, 53, 54 and 55 will be in when the casing into which these bolts are threaded is initially placed against the bracket in the same manner as that shown in Figs. 1-3 and 4. Figure 5 also shows a dotted line position in the slots 18, 23, 14 and 27 into which the shank of the bolts 53, 54, 49 and 55 are slidably mounted before these bolts are each tightened to a secure position such as the secure position shown for the bolt 49 in Fig. 2.

It should also be understood that the present invention is not limited solely to brackets having a plurality of slots of a cross shaped configuration but may be extended to brackets for example that have only a single cross shaped slot. When a bracket having such a single cross shaped slot is supported in any one of its four positions on a support member the casing of the instrument may then be securely flush mounted on this bracket by placing the shank of one of the support bolts through the lower grooved out portion of the slot and the other through its right or left grooved out portion and thence brought into threaded engagement with tapered holes in the instrument casing.

From the above description of the details of the bracket 1 it should readily be apparent that this bracket can be mounted on a vertically supported pipe 38 when the position of the parts of this bracket are in either the position shown in Fig. 1 or in the position shown schematically for these parts in Fig. 4.

It should also be understood from the above description of the bracket 1 that this bracket can be readily mounted on a horizontal support pipe 56 when the position of the parts of the bracket are in either the position shown in Fig. 3 or in the position shown schematically for these parts in Fig. 5.

Furthermore by using other suitable bolt members such as stud or cap bolt connections in place of the U-shaped bolt 39 the bracket 1 can then also be attached to a flat support surface in any one of the positions shown in Figs. 1, 3, 4 or 5.

It can thus be concluded that because of the unique construction of the cross shaped slots in the bracket 1 the bracket can readily support a casing or other object to be mounted thereon, in its upright position regardless of whether the bracket 1 is located in the position shown in Figs. 1, Fig. 3, Fig. 4 or Fig. 5.

What is claimed is:

25 A supporting bracket operative to support an instrument case in any one of four angularly displaced positions of the bracket, comprising a plate of an H-shaped configuration having four apertures substantially equally spaced from a central position on said plate, adjacent 30 ones of said apertures being substantially equally spaced from each other to accommodate correspondingly positioned mounting bolts on a flat side of said instrument case, each of said apertures having a central opening through which the head of an individually associated bolt 35 on said instrument case may extend, the opening in each of said apertures communicating with four radial slots similarly displaced approximately at right angles from each other and each of such size as to snugly receive the shank of the associated bolt for rigidly mounting 40 said instrument case on said bracket in a selected one of said positions, said H-shaped plate having an elongated, dished out portion of U-shaped configuration which when in position to support said instrument case extends away from the said flat side, and openings in 45 said U-shaped portion to accommodate mounting means for said bracket.
